UNITED STATES PATENT OFFICE

2,230,037

CLOTHESLINE AND DRIER LINK

Charles V. Hoeflich, New York, N. Y., assignor, by direct and mesne assignments, to John Spitzer, Long Island City, N. Y.

Application January 15, 1940, Serial No. 314,013

2 Claims. (Cl. 211—99)

This invention relates to a clothesline and drier link, more particularly a hanger designed primarily for suspending objects for the drying thereof, but it is to be understood that a hanger, 5 in accordance with this invention is for use in any connection for which it may be found applicable.

The invention aims to provide, in a manner as hereinafter set forth, a hanger of the class referred to, including a suspension for the objects having an inherent characteristic for fixedly connecting the suspended objects thereto without the employment of clothes pins or other independent features.

15 The invention further aims to provide, in a manner as hereinafter set forth, a hanger including resilient means so formed to thereby detachably secure garments or other objects there- 20 to without the employment of clothes pins or other separate fastener devices.

25 The invention further aims to provide, in a manner as hereinafter set forth, a hanger including spaced resilient pivotally supported sus- 30 pensions so formed as to provide for removably securing thereto garments or other objects without the employing of clothes pins or other independent fastener devices.

35 The invention further aims to provide, in a manner as hereinafter set forth, a hanger having means for expeditiously securing it to and in extended relation with respect to a panel or smooth support, and with the hanger including a carrier having means correlated with the said other means for maintaining the carrier at an upward inclination relative to the support when the hanger is suspending or not suspending garments or other objects.

40 The invention further aims to provide, in a manner as hereinafter set forth, a hanger including coupling means for expeditiously connecting it to a panel or smooth support, and a combined carrier and suspension structure pivotally attached to said means and capable of being directed upward on its pivot means to bear 45 against the support when the hanger is not in use.

45 The invention aims to provide, in a manner as hereinafter set forth, a hanger including resilient suspensions each having stretches thereof 50 helically wound about each other to form correlated gripping or clamping surfaces for detachably securing garments or objects to the suspension.

55 The invention further aims to provide, in a manner as hereinafter set forth, a hanger in-

cluding resilient suspensions each having stretches thereof helically wound about each other to form correlated gripping or clamping surfaces for detachably securing garments or other objects to the suspension, and with one of said stretches having a portion offset with respect to a corresponding portion of the other stretch to provide an opening or clearance for the mounting of the garment or other object in the suspension to enable it to be shifted between 10 the said stretches to be gripped or clamped to the suspension. 5

The invention further aims to provide, in a manner as hereinafter set forth, a hanger including a suspension of the construction aforesaid 15 having its ends formed with loops for anchoring it in position for suspending clothes or other objects.

The invention further aims to provide, in a manner as hereinafter set forth, a hanger includ- 20 ing a shiftable pivotally mounted downwardly retarded carrier and spaced resilient suspensions correlated with the carrier, and with the latter and the suspensions having coacting inherent parts for anchoring the ends of the suspensions 25 to the carrier.

The invention further aims to provide, in a manner as hereinafter set forth, a hanger for suspending objects to be dried or for any other purpose for which it is found applicable and 30 which is simple in its construction and arrangement, strong, durable, compact, thoroughly efficient in the use intended thereby, readily assembled and comparatively inexpensive to manufacture. 35

Embodying the aims aforesaid and others which may hereinafter appear, the invention consists of the novel construction, combination and arrangement of parts as will be more specifically referred to and illustrated in the accompanying 40 drawing, wherein is shown embodiments of the invention, but it is to be understood that changes, variations and modifications may be resorted to which fall within the scope of the invention as claimed. 45

In the drawing:

Figure 1 is a top plan view illustrating the support for the hanger in sectional plan and the installation of the hanger in laterally extended 50 relation with respect to the support,

Figure 2 is a fragmentary view, upon an enlarged scale in top plan, partly broken away and in section on line 2—2 Figure 1,

Figure 3 is a section on line 3—3 Figure 1, and 55

Figure 4 is a fragmentary view in top plan of a modified form of suspension.

With reference to Figure 1, the hanger 5 is of a size for the use of suspensions each formed of a single unit, but it is to be understood that the hanger may be of a size whereby each suspension will be set up of a series of coupled together units of like form as shown by Figure 4. In Figure 1, the ends of each suspension are to be anchored to a carrier or other support, whereas if the suspension would be formed of a series of coupled together units of like form, the outer units of said series would have their outer ends anchored to the carrier or other support.

15 The units which form the suspensions 6, Figure 1, are of like form and the series of units which correlate to form the elongated suspension 7 are of like form and correspond in form to the units which provide the short suspensions 6. The 20 short suspension 6 may be termed clothesline or drier link forming an element of the hanger. The elongated suspension 7 may be termed in the manner as the term applied to the suspensions 6.

25 The hanger 5 includes a pair of spaced aligned tapered circular coupling members 8 in the form of suction or vacuum cups for connection to support 9 which may be a window glass or other suitable smooth support. Each of said members 30 8 is formed at its outer end and diametrically thereof with a rectangular extension 10 provided from end to end thereof with an opening 11.

35 The hanger 5 includes a yoke shaped carrier 12 having its bight indicated at 13 and its sides 14, 15, which extend inwardly from the ends of the bight 13. The sides 14, 15 are of like form, but oppositely disposed and each has its inner end formed with a depending rearwardly inclined angle-shaped arm 16 consisting of an outer leg 17 disposed outwardly at right angles to the inner end of a side 14 or 15 and mounted in an opening 11, a depending rearwardly inclined intermediate leg 18 merging at its outer end into the outer end of the leg 17 and a rear leg 19 extending inwardly at right angles to the rear end of leg 18 and opposing the front face of a coupling member 8 below the extension 10 on the latter. The arms 16 correlate with the members 8 and constitute retarders for limiting the 50 extent of the lowering of the carrier 12 with respect to the support 9 and act to maintain the carrier 12, when it is in use at an upward inclination from its inner to its outer end.

55 Each of the sides of the carrier 12 is formed with a series of spaced inwardly extending outwardly opening substantially semi-circular portions 20 constituting holders or anchors. The portions 20 on the side 14 align with the portions 20 on the side 15 of the carrier thereby forming the latter with spaced pairs of holders, each pair is for the purpose of connecting a suspension to the sides of the carrier and also act to prevent the suspension shifting lengthwise of the sides 14, 15.

65 The sides 14, 15 of the carrier are connected together, at their inner ends by a cross member 21 acting to prevent the spreading of said sides relative to each other. The member 21 is in the form of a bar 22 formed with eyes 23 at its ends 70 for the passage of the said sides 14, 15. The eyes 23 abut the arms 16.

75 There is correlated with the carrier 12 a series of suspensions and the length of each suspension is to correspond to the distance between the sides 14, 15 of the carrier. Each suspension may con-

sist of a single unit or a series of intermediate units of a form corresponding to the form of the single unit. If a single unit is employed as a suspension it will be anchored at its ends to the sides 14, 15 of the carrier. If a series of 5 interconnected units provide a suspension, the carrier will be of a greater size than the carrier shown and the outer ends of the outer units of the series will be anchored to the sides of the carrier.

10 The unit which is employed to form the suspension 6 or each of the series of units employed to provide the suspension 7 are of like form and it is set up from a single length of resilient wire stock 24 of the desired thickness bent upon itself to form a substantially pear-shaped loop 25 open at its inner end and arranged at one end of the unit, a pair of stretches 26, 27 merging into the sides of the loop 25 and helically wound about each other to form a plurality of 20 coacting gripping or clamping surfaces 28, a substantially straight stretch 29 merging at one end into the stretch 26, a stretch 30 extended from the stretch 29 and bent upon itself to form a substantially pear-shaped loop 31 arranged at 25 the other end of the unit, a substantially semi-pear shaped stretch 32 disposed in lateral relation with respect to the stretch 29 and extended at one end from the stretch 27 and a coil 33 at the other end of stretch 32 and encompassing 30 the stretch 30 for closing the loop 31. The stretch 32 forms a clearance or opening 34 for the insertion of the object into the unit, after which it is positioned between the stretches 26, 27 and gripped or clamped to the unit by a pair 35 of coacting gripping or clamping surfaces 28. It is to be understood that the unit will be of a length to suspend more than one object.

With reference to each of the suspensions 6 the loop 25 thereof surrounds a holder 20 of the 40 carrier side 15, whereby one end of the suspension is coupled to the carrier, and the loop 31 of the suspension encompasses a holder 20 of the carrier side 14 which aligns with the aforesaid holder whereby the other end of the suspension 45 is coupled to the carrier. The length of each suspension 6 is less than the length of the bight 13 of the carrier.

When an elongated suspension 7 is formed from a series of units of like form the loops 25, 31 of an inner unit encompass respectively the loops 31, 25 of adjacent units.

With reference to Figure 3, it illustrates the position of the carrier of the hanger at the extent of the lowering movement of the carrier 25 with respect to the support to which the hanger is attached, and such position of the carrier is at an upward inclination from its inner to its outer end.

70 What I claim is:

1. In a hanger, a suspension formed of a resilient wire-like body bent upon itself to form at one end an inwardly opening loop adapted to be connected to a support, one end of the wire bent to provide a loop adapted to be connected 65 to a support, an offset part at the other end of the wire forming an entrance to the suspension for the object to be suspended and coacting object gripping portions interposed between said offset part and the first mentioned loop, said offset part including means for closing the second mentioned loop.

2. In a hanger, a suspension formed of a resilient wire-like body bent upon itself to provide an inwardly opening loop adapted to be con- 75

5 nected to a support, at its other end a loop adapted to be connected to a support, intermediate its ends a pair of stretches disposed in helically wound relation forming gripping surfaces, a part extended from one of said stretches and offset with respect to the other of said stretches

to thereby provide an entrance to the suspension for the article to be suspended, and said part being formed with means for closing said second mentioned loop.

CHARLES V. HOEFLICH. 5
